UNITED STATES PATENT OFFICE.

THOMAS G. HAWKES, OF CORNING, NEW YORK.

DESIGN FOR A GLASS VESSEL OR DISH.

SPECIFICATION forming part of Design No. 26,731, dated March 9, 1897.

Application filed February 1, 1897. Serial No. 621,574. Term of patent 14 years.

To all whom it may concern.

Be it known that I, THOMAS G. HAWKES, a citizen of the United States, and a resident of Corning, in the county of Steuben and State 5 of New York, have invented and produced a new and original Design for a Glass Vessel or Dish, of which the following is a specification, reference being had to the accompanying drawings, forming part thereof, in which—

Figure I is a bottom view of a glass dish, showing my design. Fig. II is an axial section thereof.

The leading features of my design consist of a large star figure located over the body of 15 the vessel or dish, a large central rosette, smaller rosettes located on the points of the star, intermediate rosettes located between the central rosette and the rosettes in the

points, and large rosettes located outside of the star between the points thereof. 20

The rim of the vessel or dish is provided with a wreath of large rosettes. Within this rim is a large star figure having rosettes located on the points thereof. Within the points is a ring of rosette figures, and within 25 this ring is a large central rosette, the whole forming what I call the "festoon" design.

Having thus described my invention, the following is what I claim as new therein and desire to secure by Design Letters Patent: 30

The design for a glass vessel or dish; substantially as herein shown and described.

THOMAS G. HAWKES.
